BLAST FURNACE STOCKLINE WEARING PLATES

William E. Slagley, East Chicago, and Charles F. Kirkland, Hammond, Ind., assignors to Inland Steel Company, Chicago, Ill., a corporation of Delaware

Filed May 24, 1962, Ser. No. 197,393
21 Claims. (Cl. 266—25)

The present invention relates generally to a blast furnace interior construction, and more particularly to a blast furnace wear element several of which are disposed, in a circumferential arrangement, around the interior of a blast furnace at the upper material-receiving end thereof to protect the blast furnace interior against the erosive effect resulting from the impact of descending charging material being introduced into the furnace.

A blast furnace conventionally includes an exterior metallic shell, an interior refractory lining adjacent the shell, and bell-type material-discharging means located at the top of the furnace. Material discharged into the furnace initially strikes the interior periphery of the furnace and is deflected inwardly toward a pile of previously introduced material (the furnace burden). Newly introduced material oftentimes rebounds off this pile and strikes the interior of the furnace a second time, at a lower location. If the furnace interior is not protected against the erosive effect of both the initial and rebound impacts, the refractory lining inside the furnace will be worn away in a relatively short time, and the exterior shell will be exposed to the high temperatures of the furnace interior. Rapid erosion of the refractory lining requires frequent replacement, each replacement necessitating an expensive shut-down of the furnace. Failure to replace worn refractory material in time will result in overheating of the exposed shell, thus weakening the shell which supports associated equipment and apparatus weighing about 100 tons the weight of which may cause collapse or buckling of the weakened overheated shell.

To prevent erosion of the refractory material, blast furnaces have been lined, in the area of initial and rebound impact, with cast metallic wear elements generally grouped in a multiplicity of vertically stacked and spaced tiers, each comprising a plurality of circumferentially arranged elements.

Although eliminating the problem of refractory erosion, the wear elements themselves have presented a number of additional problems. For example, because of the intense heat to which wear elements are subjected, warpage of these elements often occurred, causing ledges and crevices to be created between adjacent tiers. Descending charging material works against these ledges eventually tearing the wear elements loose from the refractory material in which they are generally embedded. The same pulling away has occurred because of the inherent gap between vertically spaced wear elements, said gap forming a crevice for descending charging material to work on. When the wear elements were pulled away they oftentimes carried the refractory material along, thereby exposing the exterior shell to the intense heat of the furnace interior. Furthermore, loss of one wear element would undermine the support of the elements in higher tiers, thus resulting in progressive failure of an entire vertical row of wear elements.

The wear element of the present invention eliminates

2

the aforementioned problems. Arranged in a group disposed circumferentially around the interior of the furnace, a subject wear element constitutes a relatively large, vertical disposed, continuously extending cast metallic plate located substantially in the area of initial and rebound impact of material discharged into the furnace. A single plate extends over the entire vertical dimension of the impact area. The plate comprises two sections, an upper wear-resistant section located in the area of initial impact, and a separate, discrete lower heat-resistant section normally contacting the furnace burden and connected to the upper section along a tightly closed seam thereby eliminating any cracks or crevices in the wear element on which descending charging material could exert a loosening effect. The surface of the subject wear element facing the interior of the furnace is smooth, continuous, and uninterrupted so that it does not interfere with the downward flow of the furnace burden.

Because the lower plate section is in tightly abutting relation with the upper plate section, the relatively intense heat, to which the burden-contacting lower section is subjected, is readily conducted from the lower to the upper section which is cooled by relatively cool gases at the furnace top. Rapidly conducting the heat away from the lower section prevents warping thereof.

Additional features which prevent warping of the wear elements are horizontally disposed top and bottom flanges extending from the vertical plate toward the furnace shell for the entire width of the plate, vertically disposed side flanges extending from the plate toward the furnace shell for the entire length of the plate, and horizontally disposed webs between the plate and the side flanges. In addition, the lowermost portion of the plate terminates at the bottom flange. Thus the entire periphery of the plate terminates at reinforcing flanges which minimize warpage of the plate.

The top of the wear element is connected to the metallic shell of the furnace in a manner which maintains the entire wear element in radially or inwardly spaced relation to the shell and mounts the wear element for vertical movement relative to the shell. The bottom of the wear element rests atop a shoulder of the furnace's refractory lining. By providing a mounting arrangement of the type just described, expansion in a vertical direction, caused by the heat to which the element is subjected, can be accommodated. In addition, each of the wear elements is slidably connected to a circumferentially adjacent wear element with a slight gap left between adjoining wear elements to accommodate expansion in a circumferential direction.

When the wear elements are initially assembled in the blast furnace, a wooden plug is inserted into and closes the gaps between adjoining wear elements. The wooden plugs and the wear elements constitute a form into which is poured a castable refractory material which, upon solidifying is associated with the wear elements and will move vertically therewith.

Located adjacent the furnace shell between the shell and the wear element is a permanent lining of a refractory material. Located between the refractory material adjacent the furnace shell and the cast refractory material is a refractory shear face material which protects both the cast and the shell-lining refractory materials from crumbling during vertical movement of the former material and associated wear elements. When

the furnace is initially lit up, the wooden plugs in the gaps between adjacent wear elements are burned out, thus opening up the normal clearance between adjacent wear elements.

Other advantages resulting from the use of wear elements constructed and arranged in accordance with the present invention are many. Installation is faster, simpler and more economical because, in a typical construction, only 26 of the subject wear elements are required to produce a circumferential arrangement protecting the furnace around its entire periphery. In comparison, several hundred wear elements have been required in arrangements utilizing vertically stacked tiers or other arrangements in accordance with the prior art.

Because the number of cast wear elements is reduced substantially, the total weight for all the elements is also reduced substantially and the simplified design resulting from the larger and fewer number of elements results in a substantial savings in the casting price per pound.

Because each wear element is attached or hung to the furnace shell, it cannot fall even if the lining, upon which the bottom of each element rests, should collapse. There is a permanent refractory lining against the furnace shell which prevent hot spots and possible shell failure even if the wear element should erode through or fall off. In addition, the wear elements are backed up with a castable refractory which provides additional protection for the shell should an element wear through.

All the plates are connected together for unitized construction. Accordingly, the unit is self-reinforcing and does not require bracing.

Inasmuch as the refractory material behind the wear elements is a cast refractory, and is poured into place after the wear elements are assembled and positioned, the time consuming old fashioned method of cutting and fitting bricks to support the wear element and to fill in behind the wear elements is eliminated.

Other features and advantages are inherent in the construction claimed or disclosed or will become apparent to those skilled in the art from the following detailed description in conjunction with the accompanying diagrammatic drawings wherein:

FIGURE 1 is an interior view of a blast furnace, in vertical section, illustrating a plurality of circumferentially arranged wear elements constructed and arranged in accordance with an embodiment of the present invention;

FIGURE 2 is an enlarged vertical sectional view of the embodiment of FIGURE 1;

FIGURE 3 is a sectional view taken along line 3-3 in FIGURE 2;

FIGURE 4 is a sectional view taken along line 4-4 in FIGURE 2;

FIGURE 5 is a sectional view taken along line 5-5 in FIGURE 1; and

FIGURE 6 is an enlarged perspective view of an embodiment of a wear element constructed in accordance with the present invention.

Referring initially to FIGURES 1 and 2 there is shown a portion of a blast furnace including a metallic exterior shell 10, an interior refractory stack lining indicated generally at 11, and bell-type material discharging means located at the top of the furnace and including a hopper 16 and a vertically movable lower bell member 12 for supporting a batch of charging material 14. When bell 12 is lowered to the position indicated by dash-dot lines 13, the material 14 flows out of the hopper 16 and follows a downward and outward path indicated by the arrows 15, said path heading toward the furnace shell.

If the descending charging material were to strike the refractory material normally lining the interior of the furnace, the erosive effect resulting therefrom would soon wear the refractory material away and expose furnace shell 10 to the intense heat within the furnace. This, in turn, would cause hot spots on the furnace shell, thus weakening the shell; and the weight of the 100 tons or

so of auxiliary equipment supported atop the furnace shell would cause the weakened shell to collapse or buckle. This problem of erosion is minimized by providing a plurality of relatively large cast metallic wear elements 20 arranged circumferentially around the interior of the blast furnace in a position to absorb the impact and avoid the erosive effect of the descending charging material.

Descending charging material striking wear elements 20 is deflected downwardly and back toward the center of the furnace where the charging material will accumulate atop a pile of material (not shown) previously charged into the furnace. Oftentimes the deflected charging material will rebound off the pile of material in the center of the furnace and head back toward the furnace shell. Rebounding charging material striking the refractory lining is an additional source of erosion. To protect the lining against rebound impact wear element 20 extends downwardly to the lowest limit of rebound impact under normal furnace operations. Thus, in essence, wear element 20 constitutes a vertically disposed, continuously extending plate located substantially in the area of initial and normal rebound impact of material discharged from the bell-type discharging means.

Each wear element 20 is connected at the top thereof to a bracket 21 attached to shell 10 and in a manner which maintains wear element 20 in radially or inwardly spaced relation to the shell and mounts the wear element for vertical movement relative to shell 10. The bottom of wear element 20 rests upon a shoulder 22 of furnace lining 11.

Located adjacent furnace shell 10 between the latter and wear elements 20 is a first or permanent refractory material 23. Located adjacent wear elements 20 between the latter and the furnace shell is a cast refractory material 24 which is vertically movable together with elements 20. Located between cast refractory material 24 and permanent refractory material 23 is refractory shear face material 25 which prevents refractory materials 23 and 24 from crumbling during the vertical movement of wear elements 20 and cast refractory material 24. The ability of element 20 and the associated refractory material 24 to move vertically accommodates vertical expansion due to heat.

Because elements 20 are connected or hung to furnace shell 10, they will not fall out or collapse even with loss of the underlying supporting refractory lining 11.

If the wear elements 20 should be eroded all the way through, the cast refractory material 24 will continue to provide protection for furnace shell 10. Furthermore, even if the cast refractory material should wear through, the permanent refractory material 23 lining the shell 10 will protect the latter from hot spots until the furnace can be shut-down and wear element 20 and cast refractory material 24 replaced.

As previously indicated, each wear element constitutes a vertically disposed continuously extending plate, indicated at 30. Each plate 30 includes an upper wear resistant section 31 and a separate, discrete lower heat resistant section 32 connected together along a closed seam 33. More specifically, referring to FIGURE 6, lower section 32 includes an upper flange 35 extending from plate 30 toward furnace shell 10. Upper section 31 includes a lower flange 34 also extending from plate 30 toward the furnace shell. The two flanges, 34, 35 are held together in tightly abutting relation by bolts 36 to define immediate flange means for the wear element 20. Accordingly, as seen in FIGURE 1, each wear element 20 presents a continuous uninterrupted smooth surface 37 disposed toward the interior of the furnace. Because of the lack of crevices, ledges or gaps, there is no starting point for the descending charging material to work on and loosen the plates. Also, the smooth uninterrupted surface provides less resistance to the downward flow of the pile of charging material within the furnace.

A typical composition for the upper wear resistant plate section is as follows:

Element:	Weight percent
C	0.55-0.65
Mn	0.50-1.00
Cr	2.00-2.50
Mo	0.25-0.45
Si	0.40-0.80
Fe	Balance

A typical composition for the lower heat resistant plate section is as follows:

Element:	Weight percent
Cr	20.0
Ni	2.0
C	1.0-1.3
Fe	Balance

The lower heat resistant plate section 32 generally is in direct contact with the furnace burden. Hot gases flowing upwardly from the reaction zone at the bottom of the furnace heat the portion of the burden in contact with plate section 32 to a temperature of 1100-1400° F. On the other hand the upper plate section 31 generally does not contact the pile of furnace burden and is exposed to a gaseous atmosphere generally having a temperature within the range 300-400° F. Because the lower section 32 is tightly connected to the upper section 31 along substantially the entire width of the lower section, heat conductivity from lower section 32 to upper section 31 is good. Accordingly, lower section 32 is maintained relatively cool, within the temperature limits of the alloy of which the plate is composed, by the rapid flow of heat from lower section 32 to upper section 31 and from there to the relatively cool gaseous atmosphere at the top of the furnace.

If plate section 32 were overheated, the peripheral edge portions thereof would tend to warp inwardly toward the interior of the furnace. This is minimized in the wear element of the present invention by the relatively large size thereof and by the composition previously described.

Additional features which prevent warpage of both the lower and upper sections of the elements are the provision of the following structural components. More specifically, referring to FIGURE 6, wear element 20 is provided with a horizontal bottom flange 40 which normally rests atop shoulder 22, and a horizontal upper flange 45, both flanges extending the entire width of plate 30. Lower plate section 32 includes vertically disposed side flanges 41, 42; and upper plate section 31 includes vertically disposed side flanges 43, 44, all of said side flanges extending the entire length of their respective plate section. Side flanges 41, 42 and 43, 44 and top and bottom flanges 45, 46 extend along the edges of the plate 30 from the plate 30 toward the furnace shell 10. Upper plate section 31 is also provided with horizontally disposed webs 47 extending between side flanges 43, 44 and plate 30. Also provided are vertically extending web portions 47 between top flange 45 and the side flanges 43, 44. All of the above-described webs and flanges together with tightly abutting flanges 34, 35 reinforce wear elements 20 and minimize warping.

Describing in greater detail the connection between elements 20 and furnace shell 10, top flange 45 of wear element 20 includes an opening 50 which slidably receives a pin 51 extending between upper and lower horizontally disposed portions 52, 53 of bracket 21 (FIG. 2). Bracket 21 also includes a vertically disposed brace portion 54 extending between horizontally disposed portions 52, 53, and a gusset element 55 which helps support the bracket 21 on shell 10.

As shown in FIGURE 2, the lowermost portion of wear element 20 terminates at bottom flange 40. This is advantageous in that it minimizes warping of the lower

portion, which would otherwise occur if the lowermost portion extended downwardly below flange 40.

Referring to FIGURES 3 and 6 bottom flange 40 includes three portions, a first portion 60 integral with plate 30 and having a width substantially the same as that of plate 30, an intermediate portion 61 integral with portion 60 and substantially narrower than portion 60, and a terminal portion 62, rectangular shaped, and substantially wider than intermediate portion 61.

Referring to FIGURE 3, terminal portion 62 is enclosed within a pair of clips 63 which hold the terminal portion in place and prevent the lower part of wear element 20 from swinging or moving in a direction toward the interior of the furnace.

Bottom flange terminal portion 62 abuts against an angle member 70 (FIG. 2) resting atop compressible refractory material 71 supported by refractory lining 11. Additional compressible refractory material 72 is provided below bracket 21 and top flange 45 of the wear element.

This compressible material 72 is immovably mounted relative to the furnace shell and accommodates the upward vertical expansion of cast refractory material 24. Also illustrated in FIGURES 1 and 2, are a frustoconical upper furnace portion 73 and a refractory lining 74.

Referring to FIGURES 1, 4 and 5, each wear element 20 is slidably connected to an adjacent wear element 20 in a circumferential arrangement by means now to be described. The side flanges 41, 42 and 43, 44 of each wear element include a plurality of vertically spaced openings 55. When the wear elements are mounted in the arrangement shown in FIGURE 1, openings 55 in a wear element are substantially aligned with similar openings in adjacent wear elements. The aligned openings slidably receive pins or bolts 56. In the arrangement illustrated in FIGURE 1, there is a gap 57 between flanges 43, 44 of adjacent wear elements 20. Gap 57, and the slidable reception of bolts 56 in the opening 55, connect the wear elements together in a manner which mounts them for movement in a circumferential direction, so as to accommodate circumferential expansion due to heat.

When the wear elements are initially assembled in the blast furnace and arranged circumferentially as illustrated in the figures, the gaps 57 are plugged up with wooden members 58 (FIG. 4). Wooden members 58 together with wear elements 20 provide a form into which refractory material 24 may be cast. When the furnace is lit up, the wooden members 58 are burned out, thus leaving a clearance between the wear elements 20 so as to accommodate circumferential expansion.

Thus the wear elements 20, when subjected to the intense heat present inside the furnace, expand circumferentially as well as vertically without damage to the interior of the furnace.

Because the refractory material 24 between wear elements 20 and furnace shell 10 can be cast into place, the tedious and complicated task of cutting and fitting bricks for placement around wear elements 20 is eliminated. Thus initial construction and subsequent replacement of the wear elements and the associated refractory material is substantially faster and less costly than in constructions utilizing wear elements of the prior art. Also facilitating installation and saving of time and money, is the reduction in the number of parts for the furnace wear lining. In a typical installation, only 26 wear elements 20 are required to line the interior of a furnace. This compares with over 500 individual elements required to be placed in the interior of a furnace when the lining was constructed in accordance with prior art teachings. Furthermore, the simplified design of the wear elements and the relatively large size thereof, results in a savings in the cost of casting the lining for the furnace. Also reduced is the total

weight for lining thereby resulting in a savings in material and in the cost thereof.

The above-described embodiments being exemplary only, it will be understood that the present invention comprehends organizations differing in form or detail from the presently described embodiments. Accordingly, the invention is not to be considered as limited save as is consonant with the scope of the following claims.

What is claimed is:

1. In a blast furnace including a shell, a lining, and material discharging means at the top thereof:

a plurality of circumferentially arranged, vertically disposed wear elements around the interior of the furnace;

each wear element constituting a vertically disposed plate extending continuously along the vertical dimension of the area of initial and normal rebound impact of material discharged from said discharging means;

means on said furnace shell and means on said wear elements cooperating to maintain the wear elements in inwardly spaced relation to the furnace shell and to mount said wear elements for vertical movement relative to the furnace shell;

a first relatively stationary refractory material, adjacent the furnace shell, between said shell and said wear elements;

a cast second refractory material, adjacent said wear elements, between the latter and said shell, and vertically movable with said wear elements; and a layer of refractory shear face material between said first and second refractory materials.

2. In a blast furnace as recited in claim 1 and comprising:

shoulder means on said furnace lining; and means at the bottom of each plate for resting on said shoulder means;

the lowermost part of each plate terminating at said shoulder means.

3. In a blast furnace as recited in claim 2 wherein said means at the bottom of said plate comprises:

a first portion integral with the plate and substantially the same width as the latter;

an intermediate portion integral with said first portion and substantially narrower than the first portion; and a terminal portion integral with said intermediate portion and wider than the intermediate portion; and means, engaging said terminal portion, for holding the plate against movement toward the interior of the furnace.

4. In a blast furnace as recited in claim 1 wherein said cooperating means comprises:

a plurality of brackets each connected to said shell and each extending inwardly therefrom adjacent the top of a respective plate;

a pin extending vertically from said bracket; a flange extending from each plate, at the top thereof, and toward said shell;

and an opening in said flange for slidably receiving said pin.

5. In a blast furnace as recited in claim 1 wherein each plate comprises:

an upper wear-resistant section in the area of initial impact of said discharged material;

a lower heat-resistant section separate and discrete from said upper section;

and means connecting said lower section to said upper section along a closed seam.

6. In a blast furnace as recited in claim 5 wherein said connecting means comprises:

a flange at the bottom of said upper section;

a flange at the top of said lower section;

and means for holding said flanges together in relatively tightly abutting relation, to prevent entry of discharged material between said sections and to facilitate

heat transfer from the lower to the upper section.

7. In a blast furnace as recited in claim 1 wherein each wear element comprises:

a top flange extending from the uppermost part of said plate toward said furnace shell;

a bottom flange extending from said plate toward the furnace shell; the lowermost portion of said plate terminating at said bottom flange;

said plate having a relatively smooth uninterrupted surface facing the furnace interior.

8. In a blast furnace as recited in claim 7 wherein each wear element comprises:

a vertical flange along each side of said plate and extending from the plate toward the furnace shell; horizontally disposed web means between the plate and each vertical flange;

and intermediate flange means, substantially horizontally disposed, between said top and bottom flanges, and extending from the plate toward the furnace shell.

9. In a blast furnace as recited in claim 1 wherein: each wear element is circumferentially spaced from an adjacent wear element to provide a relatively small clearance between adjacent wear elements;

each of said two adjacent wear elements having a vertically disposed flange extending from a respective plate toward the furnace shell along a respective opposite side of said clearance;

aligned openings in said flanges; and bolt means slidably received in the aligned openings to connect said adjacent wear element and mount them for circumferential movement.

10. In a blast furnace including a shell, a lining, and bell-type material discharging means at the top thereof:

a plurality of circumferentially arranged, vertically disposed wear elements around the interior of the furnace;

each wear element constituting a plate extending continuously along the vertical dimension of the area of initial and normal rebound impact of material discharged from said bell-type discharging means;

each plate having a wear-resistant upper section, and a heat-resistant lower section connected to said upper section along a closed seam;

means on said furnace shell and means at the top of each plate cooperating to maintain the plate in inwardly spaced relation to said furnace shell and to mount the plate for vertical movement relative to the shell;

shoulder means on said furnace lining; and means at the bottom of each plate for resting on said shoulder means;

the lowermost portion of each plate terminating at said shoulder means;

a first relatively stationary refractory material adjacent the furnace shell, between said shell and said wear elements;

a cast second refractory material, adjacent the wear elements, between the latter and said shell, and vertically movable with said wear elements;

and a layer of refractory shear face material between said first and second refractory materials;

each plate having a relatively smooth uninterrupted surface facing the furnace interior.

11. In a blast furnace as recited in claim 10 and comprising:

means connecting adjacent wear elements together and mounting said wear elements to accommodate circumferential expansion and contraction of adjacent wear elements.

12. A blast furnace wear element for use, with a plurality of circumferentially arranged other wear elements identical to said first recited wear element, to line a portion of the interior of a blast furnace having a shell,

a lining and material discharging means at the top thereof, said wear element comprising:

a plate extending vertically and continuously for a distance substantially equal to the vertical dimension of the area of initial and normal rebound impact for material discharged from said discharging means; 5
said plate having a relatively smooth, uninterrupted front surface, along its entire length, for disposition toward the interior of said furnace;

said plate having a rear surface opposite said front surface; 10
said plate having an upper wear-resistant section, and a lower heat-resistant section separate and discrete from the upper section and connected to said upper section along a single closed seam;

means at the top of said plate for hanging said plate in inwardly spaced vertically movable relation to the shell; 15
and a flange at the bottom of said plate, extending rearwardly from said plate, for resting on said furnace lining;

the lowermost part of said plate terminating at said bottom flange. 20

13. A wear element as recited in claim 12 wherein said means at the top of said plate comprises:

a top flange extending rearwardly from said plate in the same direction as said bottom flange; 25
and a pin-receiving opening in said top flange.

14. A wear element as recited in claim 12 and comprising:

a flange at the bottom of said upper section; 30
a flange at the top of said lower section;

and means for holding said flange together in relatively tightly abutting relation, to prevent entry of discharged material between said sections and to facilitate heat transfer from the lower to the upper section. 35

15. A wear element as recited in claim 12 and comprising:

a top flange extending from said plate in the same direction as said bottom flange; 40
a vertical flange along each side of said plate and extending rearwardly from the plate;

web means between the plate and a respective vertical flange; 45
and intermediate flange means substantially horizontally disposed, between said top and bottom flanges, and extending rearwardly from the plate.

16. A wear element as recited in claim 12 wherein said bottom flange comprises:

a first portion integral with the plate and substantially the same width as the latter; 50
an intermediate portion integral with said first portion and substantially narrower than the first portion; and a terminal portion integral with said intermediate portion and wider than the intermediate portion. 55

17. In a blast furnace including a shell, a lining and material-discharging means at the top of the furnace:

a vertically disposed wear element extending continu-

ously along the vertical dimension of the area of initial and normal rebound impact of material discharged from said discharging means;

means on said furnace shell and means on said wear element cooperating to maintain the wear element in inwardly spaced relation to the furnace shell and to mount the wear element for vertical movement relative to the furnace shell;

a cast refractory material adjacent said wear element, between the latter and the furnace shell;

means, including means on said wear element engaging said cast refractory material, for moving the cast refractory material vertically in response to said vertical movement of said wear element;

and a layer of stationary refractory material between said movable cast refractory material and the furnace shell. 18. In a blast furnace as recited in claim 17 and comprising:

a flange, at the bottom of said wear element, extending from the wear element toward the furnace shell; said flange underlying said movable refractory material. 19. In a blast furnace as recited in claim 17 wherein the wear element and the cast refractory material are movable along a vertical path, said furnace further comprising:

compressible refractory material immovably mounted relative to the furnace shell and located in said vertical path to accommodate movement along said vertical path. 20. A wear element as recited in claim 12 wherein:

said upper plate section is composed of a relatively wear-resistant material;

and said lower plate section is composed of relatively heat-resistant material different than the material of which said upper plate section is composed. 21. A wear element as recited in claim 12 and comprising:

a vertical flange along each side of said plate and extending rearwardly from the plate;

and openings in each flange for receiving circumferential-movement-accommodating pins. 40
